UNITED STATES PATENT OFFICE.

CHARLES F. RAMAGE, OF LANGDON, NORTH DAKOTA.

AMUSEMENT DEVICE.

Application filed March 28, 1927. Serial No. 179,111.

This invention relates to an amusement device of the motor driven vehicle type and has for its object to provide, in a manner as hereinafter set forth, a device of such 5 class for turning a complete somersault during the travel thereof for imparting a thrill to the driver of the machine without injury and under such conditions affording great amusement when the device is used, not only 10 to the driver, but to onlookers.

A further object of the invention is to provide, in a manner as hereinafter set forth, an amusement device of the motor driven vehicle type including means to provide for 15 the device to make, from an upright position during the travel thereof, a complete somersault and land in an upright position and continue on its journey, under such conditions affording great amusement during the 20 travel of the device.

Further objects of the device are to provide, in a manner as hereinafter set forth an amusement device of the motor driven type, which is comparatively simple in its 25 construction and arrangement, strong, durable, conveniently set to provide for the somersaulting thereof, amusing when used, and comparatively inexpensive to set up.

With the foregoing and other objects in 30 view the invention consists of the novel construction, combination and arrangement of parts as hereinafter more specifically described and illustrated in the accompanying drawings, wherein is shown an embodiment 35 of the invention, but it is to be understood that changes, variations and modifications can be resorted to which fall within the scope of the claims hereunto appended.

In the drawings wherein like reference 40 characters denote corresponding parts throughout the several views:

Figure 1 is a side elevation of an amusement device, in accordance with this invention and in normally upright position.

Figure 2 is a top plan view thereof.

Figure 3 is a side elevation of the device with the parts thereof positioned to provide for the device turning a complete somersault in upright position or rather 50 normal upright position.

Figure 4 is a view similar to Figure 3 with the parts positioned after the device has turned the complete somersault and is assuming an upright position.

Figure 5 is a fragmentary view in section,

illustrating the rear axle and one of the eccentric tilting members for the device.

Figure 6 is a detail of one of the release members.

Figure 7 is a fragmentary view illustrating the latching device for the eccentric tilting members.

Referring to the drawing in detail 1 denotes a chassis of a motor driven vehicle, 2 the engine, 3 the clutch lever, 4 the steering post, 5, 6 the front wheels, 7 the front axle, 8 the rear axle, 9 the vehicle springs and 10, 11 the rear wheels of the vehicle. The foregoing elements are of known construction.

The chassis can be tilted to the position 70 shown in Figure 3 with respect to the front wheels of the vehicle.

Carried by the chassis 1 is a superstructure in the form of a frame of semi-circular contour consisting of a pair of opposed sections of like construction, arranged in spaced relation and connected together at their upper ends. The lower ends of the sections are connected to the sides and front of the chassis. As each section of the superstructure is of the same construction but one will be described as the description of one applies to the other. Each section consists of a semi-circular bar 12 of appropriate height and which abuts against the ends of a side bar of the chassis, see Figure 1, as well as being secured to the ends of such side bar by angle bars 13, 14. The ends of the bar 12 depend below that side bar of the chassis to which the bar 12 is secured. The bar 12 is 80 furthermore connected to a side bar of the chassis by brace members 14, 15, 16, 17, and 18. The lower ends of said brace members are fixedly secured to the side bar of the chassis and the upper ends thereof fixedly 90 secured to the bar 12. The brace members 15, 16 are vertically disposed and the other brace members are arranged at an inclination.

The brace members of one section of the superstructure are arranged in alignment with respect to the brace members of the other section of the superstructure and the brace members of one section at their upper ends are connected to the brace members of 100 the other section, by the coupling bars 19. The bars 19 are of angle shape in cross section.

Secured to the brace members 15, 16 as 110 well as arranged therebetween and project-

ing laterally therefrom, and further connected with the chassis 1, is a cage 20 of less height than the height of the brace members 15, 16. Within the cage 20 is a seat 21 for the driver and when somersaulting the driver will be strapped to the seat. The cage 20 is provided with a suitable entrance door so that the driver can enter the compartment provided by the cage. The bottom of the cage has floor boards. A tank for gasoline is indicated at 22 and is arranged within the compartment formed by the cage and below the seat or chair 21. The cage 20 includes front, side and top walls and the bottom thereof is formed by the floor boards. The compartment formed by the cage is of sufficient size so that the driver can handle the steering column and clutch said brake levers as well as a latching device for the eccentric tilting members to be presently referred to.

Fixedly secured to the forward ends of the bars 12 is a rigid braking device 23, disposed transversely with respect to the chassis 1 and having each of its ends formed with a brake member, as indicated at 24 and which opposes a front wheel. When the rear end of the chassis is tilted upwardly, in a manner as hereinafter set forth, the brake members 24 are positioned under the front wheels, engage the ground and forward travel of the vehicle. The rear faces of the brake members are of arcuate contour.

35 Loosely mounted on the rear axle 8, in proximity to each rear wheel, is a collar 25 retained from shifting lengthwise with respect to the rear axle by a pair of spaced stop collars 26 secured to the rear axle by set screws 27. Secured to each collar 25 and bodily shiftable therewith and normally held in an elevated position is an eccentric tilting member consisting of convolute bar 28, having its upper end, as indicated at 29, partly enveloping the collar 25 and fixedly secured therewith by a holdfast device. Extended from the upper end 29 of the bar 28, is a series of inclined, spaced spokes 31 providing bracing means 40 for the bar 28. The outer face of the bar 28 throughout, is provided with spaced tread members 32. One of the spokes 31 is positioned at the lower end of the bar 28, and the other spokes 31 are arranged between the ends of the bar and in spaced relation. The spokes 31 are of different lengths with respect to each other. The tilting members are connected together by a coupling bar 33, which is disposed transversely with respect 45 to the chassis 1 and has the ends thereof connected to the inner faces of the bars 28 intermediate the ends thereof.

60 The coupling bar 33 form an element of a latching device, for maintaining the eccentric tilting members in an elevated position

and clear of the ground, when the rear wheels of the vehicle are travelling from the ground. The latching device includes a resilient latching member 34 which depends from a chassis cross bar, indicated at 35. The latching member 34 is adapted to engage under the coupling bar 33, as shown in Figure 7 for the purpose of maintaining the eccentric tilting members in an elevated position. The latching member 34 is formed with an angular extension 36 at its upper end, which is secured to the chassis cross bar 35, by the holdfast device 37. The latching member 34 is furthermore formed at its lower end with a forwardly directed apertured lug 38, to which is attached a pull rod 39, having its forward end loosely connected as at 40, to the lower end of a shifting lever 41, which is pivoted as at 42, to a chassis cross bar 43. The lever 41 extends up into the compartment formed by the cage 20 and within convenient reach of the operator or driver. When the upper end of the lever 41 is pulled rearwardly, the latching member 34, is moved from engagement with the coupling bar 33, and the eccentric tilting members will then fall by gravity to the ground and provide for the upward tilt of the rear end of the device, in a manner as shown in Figure 3.

65 Pivottally connected to a hanger 44, which is secured to the front axle 7, by the holdfast device 45 is a release member 46. Two release members are provided, as well as two hangers, and each release member is positioned in proximity to a front wheel. Each release member projects forwardly from the hanger 44, as well as extending rearwardly therefrom and that part of the release member 46 which extends rearwardly from the hanger 44 is of greater length than the portion which projects forwardly from said hanger. The pivot between the release member and the hanger is indicated at 47. The rear terminal portion of the release member is bevelled as indicated at 48. Each release member is spring controlled and its controlling spring is indicated at 49. The controlling springs 49 are connected to the superstructure, in proximity to the brace members 18, that is in proximity to the upper ends of said brace members 18 as indicated at 50. The lower end of each of the springs 49 is extended as at 51, and attached to an eye 52 carried by the forward end of a release member 46. When it is desired to have the vehicle turn a complete somersault, the vehicle is driven at a fair rate of speed, for a required distance, then the driver releases the eccentric tilting members from the position shown in Figure 1. The tilting members then fall to the ground and as the machine travels forward, the tilting members elevate the rear end of the vehicle causing thereby the rigid brake, at the front thereof, to con-

tact with the ground, whereby the vehicle is caused to make a complete somersault and land in an upright position and with the tilting members, when the vehicle lands, shifted 5 so as to be extended in an elevated position.

The superstructure serves a double function, one of which is that it provides a rounded surface which permits the vehicle to roll end over end and the other of which 10 is to protect the driver from injury when the vehicle is forced to make a complete somersault. The spring controlled release members are to break the jar when the vehicle rights itself and during the starting 15 of such action the release members are positioned as shown in Figure 4.

It is thought the many advantages of an amusement device, in accordance with this 20 invention can be readily understood, and although the preferred embodiment of the invention is as illustrated and described, yet it is to be understood that changes in the 25 details of construction can be had which will fall within the scope of the invention as claimed.

What I claim is:

1. An attachment for motor driven vehicles to provide for a complete somersault thereof during its travel, normally latched 30 eccentric tilting members adapted to be loosely connected to the rear of the vehicle and further adapted when released to tilt

the rear end of the vehicle during the travel thereof, a rigid brake secured to the front of the vehicle forward of the front wheels 35 thereof and adapted to contact with the ground when the rear end of the vehicle is tilted by said elements, and a superstructure of semi-circular contour adapted to be secured to the vehicle and providing a rolling 40 action for the latter during the somersault.

2. An attachment for motor driven vehicles to provide for a complete somersault thereof during its travel, normally latched eccentric tilting members adapted to be 45 loosely connected to the rear of the vehicle and further adapted when released to tilt the rear end of the vehicle during the travel thereof, a rigid brake secured to the front of the vehicle forward of the front wheels 50 thereof and adapted to contact with the ground when the rear end of the vehicle is tilted by said elements, a superstructure of semi-circular contour adapted to be secured to the vehicle and providing a rolling action 55 for the latter during the somersault, and rearwardly extending spring controlled, pivoted release elements adapted to be connected to the forward portion of the vehicle and acting to absorb shock, on the righting of the vehicle at the end of the somersault.

In testimony whereof, I affix my signature hereto.

CHARLES F. RAMAGE.
